UNITED STATES PATENT OFFICE.

JOHN ALBACH, OF MUSKEGON, MICHIGAN.

AUTOMOBILE RADIATOR.

Application filed December 14, 1921. Serial No. 522,278.

To all whom it may concern:

Be it known that I, JOHN ALBACH, a citizen of the United States, residing at Muskegon, in the county of Muskegon and

State of Michigan, have invented certain new and useful Improvements in Automobile Radiators, of which the following is a specification.

This invention relates to automobile radiators and more particularly to cores for such radiators.

The object of the invention is to so construct such a core as to provide for expansion of the water tubes on freezing of the water therein and thus prevent bursting of these tubes.

Another object is to so construct a core of this character which may be used on any make of car using water cooling systems and in which the fins are readily removable for repairs and the like.

Another object is to provide such a core the water tubes of which have lateral offsets therein with the fins located on opposite sides of the offsets thereby providing unrestricted portions of the tubes which will expand on the freezing of the water therein and thus prevent bursting of the tubes.

With these and other objects in view, the invention consists in certain novel features of construction as hereinafter shown, described and claimed.

In the accompanying drawings:

Figure 1 represents a front elevation of a radiator constructed in accordance with this invention.

Fig. 2 is an enlarged detail horizontal section taken on the line 2—2 of Fig. 1, and

Fig. 3 is a detail vertical section of the radiator core.

In the embodiment illustrated, the usual radiator frame 1 is shown having the usual upper and lower water chambers 2 and 3 which are connected by the circulating tubes 4 which constitute a part of this invention.

The core 5 which is mounted in the frame 1 and which embodies this invention comprises a plurality of upright flat water tubes 4 any desired number of which may be employed six being here shown, each of which is constructed from a single sheet of metal, preferably brass, united at the rear by a double lock seam 6 which is soldered to render it water-tight. Each of these tubes 4 has a laterally offset portion 7

formed midway the width thereof as is shown clearly in Fig. 2 which offset portion 7 forms an expansion chamber in case of freezing of water in the tube as will be 60 hereinafter more fully described.

These tubes 4 as shown clearly in Fig. 4 are arranged in laterally spaced relation in the frame 1 with their upper and lower ends communicating respectively with the water chambers 2 and 3 of said frame to provide for the circulation of water through them before it enters the water jacket of the engine as is usual in radiators of this character.

Arranged between the upright tubes 4 are a plurality of fins 8 one of which is arranged between the front portions 9 of the tubes 4 and another between the rear portions 10 thereof said fins terminating at the 75 ends of the offset portion 7 as is shown clearly in Fig. 2 whereby said offset portion 7 is unrestricted and thus permitted to expand laterally on freezing of water in the tube which prevents bursting of the 80 tubes. These fins 8 are preferably constructed in serpentine form as shown clearly in the drawings with the alternating curved portions 11 thereof contacting with the opposed tubes 4. With this arrangement of 85 the fins the air entering from the front of the radiator will pass through the passages 12 formed by the front fins and striking the offset portion 7 of the tubes at the rear of these fins will be deflected into the passages 13 of the rear fins, thus the air will be buffeted back and forth against the walls of the tubes as it passes between them.

As shown in Fig. 2 the thickness of the 95 radiator core from front to rear includes two series of the fins 8 the tubes 4 being of a width corresponding to the width of the two series of fins plus the offset portion 7 in said tubes.

The fins 8 may be constructed of any suitable thin sheet metal but preferably are made of brass which is a good conductor of heat so that the heat from the water in the tubes is readily transmitted thereto and cooled by the passage of the air through the conduits 12 and 13 formed by the fins.

From the above description it will be obvious that a radiator core 5 constructed as herein shown and described will prevent all 110 possibility of bursting of the tubes of the radiator incident to freezing of the water

therein and that the water will be quickly cooled by the arrangement of fins between the tubes.

The preferred embodiment of the invention is disclosed in the drawings and set forth in the specification, but it will be understood that any modifications within the scope of the claimed invention may be made in the construction without departing from the principle of the invention or sacrificing any of its advantages.

I claim:

1. A radiator of the class described comprising a plurality of flat tubes constructed from a single sheet of metal having a double lock seam at the rear thereof, said tubes being offset laterally midway their widths and a plurality of serpentine fins arranged between said tubes with the oppositely disposed curved portions thereof contacting with the opposed tubes, two series of said

fins being employed one at the front and one at the rear of the radiator, each series terminating adjacent the offset portion in the tubes whereby the tubes are provided with expansible portions to prevent bursting of the tubes on the freezing of the water therein.

2. In a radiator of the class described, a series of flat tube members, each having a rear portion, an offset intermediate portion and a front portion, the front and rear portions being in parallel, a series of corrugated fin members positioned between the said rear portions and extending inwardly to said offset portion, and a series of corrugated fin members positioned between the said front portions and extending rearwardly to said offset portions.

In testimony whereof, I affix my signature hereto.

JOHN ALBACH.
